UNITED STATES PATENT OFFICE.

THEODORE L. VALERIUS, OF FORT ATKINSON, WISCONSIN, ASSIGNOR TO
THE CORNISH, CURTIS & GREENE MANUFACTURING COMPANY, OF
SAME PLACE.

DESIGN FOR A BOTTLE.

SPECIFICATION forming part of Design No. 30,533, dated April 11, 1899.

Application filed October 2, 1897. Serial No. 653,863. Term of patent 14 years.

To all whom it may concern:

Be it known that I, THEODORE L. VALERIUS, a citizen of the United States, residing at Fort Atkinson, in the county of Jefferson and State 5 of Wisconsin, have invented and produced a new and original Design for Bottles, of which the following is a specification, reference being had to the accompanying drawing, forming part thereof.

10 My invention consists in a novel design for bottles, which is illustrated in the accompanying drawing, and the essential feature of which resides in a groove or depression in the bottom of the bottle, extending transversely 15 across the same, as shown.

The bottle is represented as having a body A of circular form in cross-section and a long slender neck B; but the distinctive feature of the design is the cross-groove C in the bottom of the bottle.

What I claim as my invention is—

20 The design for a bottle, as shown and described.

In witness whereof I hereunto set my hand in the presence of two witnesses.

THEODORE L. VALERIUS.

Witnesses:

S. S. SWASEY,
H. H. CURTIS.
